[57] CLAIM

The ornamental design for an end closure for a container, as shown and described.

DESCRIPTION

FIG. 1 is an environmental perspective view of an end closure for a container showing my new design;

FIG. 2 is a top view thereof in a closed position;

FIG. 3 is a top view thereof in an open position;

FIG. 4 is a bottom view thereof in a closed position; and,

FIG. 5 is a partial sectional view thereof in an open position.

The broken line showing of a portion of a container in FIG. 1 is for illustrative purposes only and forms no part of the claimed design.

FIG. 1

FIG. 2

FIG. 3

FIG. 4

FIG. 5
